UNITED STATES PATENT OFFICE.

PETER MEYER, OF COLOGNE-NIPPES, GERMANY.

TABLE-FORK CLEANER.

SPECIFICATION forming part of Letters Patent No. 627,622, dated June 27, 1899.

Application filed August 12, 1898. Serial No. 688,465. (No model.)

To all whom it may concern:

Be it known that I, PETER MEYER, a citizen of the Empire of Germany, residing at Cologne-Nippes, Germany, have invented certain new and useful Improvements in Table-Fork Cleaners, of which the following is a specification.

The present invention relates to an apparatus for cleaning table-forks, whatever may be the opening of the teeth thereof, by means of a cleaning substance, such as soft leather, textile fabric, and the like.

It happens frequently, and particularly in hotels, eating-houses, boarding-houses, and the like, that housemaids called for cleaning the various covers in use every day do not accomplish this work with great care, and very often there remain between the teeth of the table-forks articles of food which are removed with great difficulty on account of the small opening between the teeth of these table-forks. Besides the uncleanliness the use of these table-forks thus insufficiently cleaned is very injurious to health, said table-forks being capable of transmitting contagious maladies.

The above-mentioned inconveniences are done away with by means of the apparatus forming the object of the present invention and allowing the table-forks to be perfectly cleaned by causing the teeth thereof to pass between the coils of a spiral spring advisably adjusted and covered over with a cleaning substance, as more fully described and claimed hereinafter.

In the accompanying drawings a practical form of construction of the improved table-fork cleaner is shown, in which—

Figure 1 is a front elevation of the device, and Fig. 2 a side elevation of the same. Fig. 3 is a perspective view of the device, showing the cleaning material applied to the spring.

In the figures similar reference-letters denote similar parts.

45 *a* is a supporting-frame provided with a handle.

b indicates spheres for securing the spring hereinafter mentioned.

c is a metallic rod threaded at its lower end 50 and joined to spheres *b*.

d is an adjusting-nut for the spring.

e are caps holding the spring, *f* the spiral

spring, and *g* a guiding-stem for the spring. (Shown in dotted lines.)

The supporting-frame *a* of the device is 55 made of any suitable material and provided with a handle. On the frame *a* are secured, by means of screws and a seat for each sphere, the spheres *b*, each having in it a socket. These spheres project from the center of each 60 end of the front of the frame perpendicularly to the same, and the said sockets are sunk in the spheres to face each other and be in the same line. Into these sockets are set the ends of the rod *c*, threaded at its lower end, for 65 screwing a hand-nut *d* thereon. The rod *c* is surrounded by the spiral spring *f*. The upper end of the rod *c* has on it a cap *e'* corresponding to the cap *e* below and resting against the sphere *b* as the cap *e* rests against the nut 70 *d*. The said spiral spring *f* has its ends applied against the cap *e* and cap *e'*, allowing said lower cap *e* to be brought nearer the cap *e'* or to be removed therefrom, thus serving to give to the coils of the spring *f* an opening 75 between them corresponding to the opening of the teeth of the table-fork to be cleaned. The spiral spring *f* is held by the spring-stem *g*, arranged parallel with the rod *c* within the coils of the said spring, the ends of said spring- 80 stem *g* extending into cavities made, respectively, in the upper and lower sides of the supporting-frame *a*. The said spring-stem passes through the caps *e* and prevents the spiral spring from bending and escaping from 85 said caps when packing and cleaning.

The device is used as follows: First, the spiral spring *f* is adjusted by means of screwing the nut *c* until the openings between the coils correspond with the openings between 90 the teeth of the table-fork to be cleaned. Then the cleaning material is placed upon the spring and the table-forks are rubbed upon this material, so that the spring-coils penetrate between the teeth of said table-fork to clean the 95 inner faces thereof.

Having thus described my invention, what I claim, and desire to secure by Letters Patent, is—

1. In a tool for scouring cutlery, the combination of a spiral spring arranged and adapted to allow the blade or tines of a knife or fork to be rubbed backward and forward between its coils, and cleaning material applied 100

to and covering said coils, substantially as set forth.

2. In an implement for scouring cutlery, the combination of a frame with a spiral spring mounted thereon, caps for the ends of the said spring means for adjusting one of the said caps to compress or relax the said spring, the other cap remaining stationary, and cleaning material applied to and covering said spring, substantially as set forth.

3. In combination with a frame and a screw-threaded rod mounted parallel thereto in attachments of the said frame, a spiral spring surrounding the said rod, a pair of caps at 15 the ends of the said spring and a nut turning on the threads of the said rod to force one of the said caps against the said spring for compressing the same at will, substantially as set forth.

20 4. In a table-fork cleaner, the combination of a frame, provided with a handle, two spheres, each having a seat secured to said frame and provided with sockets opposite

each other, a rod threaded at its lower part the ends of said rod being located in the holes 25 of said spheres, a hand-nut, screwed on said rod, two caps traversed by said rod and arranged respectively, one below the upper sphere, and the other above the hand-nut, a spiral spring surrounding said threaded rod 30 and pressed by means of the hand-nut between said caps to cause the openings between its coils to correspond with the openings between the teeth of the fork to be cleaned, said spring being covered with cleaning material, the fork being rubbed thereon, and a spring-stem *g* attached to said spring and serving to hold it in place substantially as set forth.

In testimony that I claim the foregoing as 40 my invention I have signed my name in presence of two subscribing witnesses.

PETER MEYER.
